CLAIM

The ornamental design for an adjustable bed, as shown and described.

DESCRIPTION

FIG. 1 is a top, front, left side perspective view of an adjustable bed showing our new design, in which the bed board is removed for ease of illustration of the internal structure;

FIG. 2 is a top, rear, right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is an enlarged view of the encircled portion labelled 8 in FIG. 1;

FIG. 9 is a top, front, left side perspective view thereof, in which one side of the bed rail is in a collapsed position;

FIG. 10 is a top, front, left side perspective view showing the adjustable bed with the bed board; and,

FIG. 11 is a top, front, left side perspective view showing the adjustable bed with the bed board in a folded state.

(Continued)

The broken lines in the drawings illustrate portions of the adjustable bed which form no part of the claimed design.
